[57] CLAIM

The ornamental design for a miniature rocking chair, as shown and described.

DESCRIPTION

FIG. 1 is a right-front perspective view of a miniature rocking chair showing my new design;

FIG. 2 is a right side elevational view, the left side being a mirror image thereof;

FIG. 3 is a bottom plan view;

FIG. 4 is a rear elevational view;

FIG. 5 is a top plan view;

FIG. 6 is a right-front perspective view showing a second embodiment of my new design;

FIG. 7 is a right side elevational view of FIG. 6, the left side being a mirror image thereof;

FIG. 8 is a bottom plan view of FIG. 6;

FIG. 9 is a rear elevational view of FIG. 6; and,

FIG. 10 is a top plan view of FIG. 6.
